UNITED STATES PATENT OFFICE

2,631,301

COMBINED CONVALESCENT COUCH AND
BEDPAN SUPPORT FOR BABIES

Raymond F. Hyland, Rochester, N. Y.

Application August 29, 1951, Serial No. 244,145

3 Claims. (Cl. 5—90)

1

The present invention relates to a combined convalescent couch and bedpan holder, and more particularly to a device for supporting a person, whose lower limbs are in a cast, in a prone position with a bedpan so located that the person can evacuate at will into the bedpan.

In a still more specific aspect, the invention relates to a device for holding a baby, that is in a cast, in position so that when the baby evacuates it will do so into a bedpan and not soil itself or the bedclothes.

When a child is afflicted with the condition known as "congenital hip," the child has to be placed in a cast which holds the upper portion of the child's legs at right angles to the body, and the child has to be kept in that cast for a year or more. The child has to stay in the cast both while asleep and while awake. Because of the baby's age and condition a special rest or couch is ordinarily procured for it. The conventional couch or rest for this purpose comprises a metal frame across which two longitudinally-spaced pieces of canvas are stretched, the child's head and upper portion of the child's body resting on one piece of canvas, and the lower portion of the child's limbs resting on the other piece of canvas. The space between the two pieces of canvas is provided so that the child can evacuate into a bedpan placed under this space.

Inasmuch as the correction of a condition such as "congenital hip" is made while the child is in infancy, the child because of its age is not aware that it should remain still while evacuating. With the device heretofore used, therefore, the canvas of the support is frequently soiled as are also the bedclothes.

A primary object of the present invention is to provide a device in which a child afflicted with a condition such as "congenital hip" may be placed while convalescing and which will support the infant comfortably while restraining the baby from movement while urinating or defecating.

Another object of the present invention is to provide a device of the character described which may serve as an actual couch on which the child can repose at all times and yet which will hold the child securely against twisting or turning during evacuation.

Further objects of the invention are to provide a device of the character described which will be simple in construction, easy to make, low in cost and easy to keep clean.

Still other objects of the invention will be apparent hereinafter from the specification and from the recital of the appended claims.

2

In the drawing:

Fig. 1 is a perspective view of a combined couch and bedpan support made according to one embodiment of this invention;

Fig. 2 is a plan view on a somewhat reduced scale of this device and illustrating how it is used, the hold down straps being omitted for clearness in illustration; and

Fig. 3 is an end elevation of the device.

The device comprises a support or rest 10 which may be made of wood, metal, plastic, metal frame and canvas, or any other suitable material or materials. It has preferably a plane upper face. The support 10 has a centrally disposed elongated opening 11 extending from one end of the support toward the other for a little more than half the length of the support. This opening is bounded along its sides by the two leg portions 12 and 13 of the support. Secured to the upper face of the support 10 at the inner terminal end of the slot 11 to project upwardly from the support is a saddle member 15 which has an arcuate seat or socket 16 formed therein. Projecting rearwardly from the saddle and extending along the opposed edges of the leg members 12 and 13 are two erect wings or guards 18 and 19. These are provided, adjacent the saddle board 15, with aligned arcuate sockets or recesses 20 and 21, respectively, to receive the leg portions of the child's cast. The axis of the sockets 20 and 21 is in the embodiment illustrated at right angles to the axis of the socket 16.

Secured to the underside of the support 10 beneath the legs 12 and 13 is a receptacle or chamber 25. This receptacle is rectangular in cross section. It is closed at its sides and bottom, and at its inner end, the inner end wall being denoted at 26. It is open at its top to register with the opening 11 between the legs 12 and 13 of the support; and it has its outer end open so that a bedpan 28 can readily be slid into and out of it.

In a congenital hip condition, a baby such as shown at B in Fig. 2 is placed in a generally T-shaped cast 30 which surrounds the child about the waist and is made so as to hold the upper portions 31 of the child's two legs at right angles to the body. The child's lower limbs 32 may be free, but the child's legs are rigidly held at their upper portions by the cast. The upper portions of the child's body and its arms 34 are, of course, free. The cast is also left open, as denoted at 35, both in the front and back so that the child can freely evacuate.

In use the couch is ordinarily placed in the baby's crib on top of the mattress; and the rest or support 10 including the leg portions 12 and 13

can be padded if desired for comfort of the infant. The guards or wings 18 and 19 are made of sufficient height to project above the legs of the baby so that when the baby lies on the support 10 with its legs on the legs 12 and 13 of the support, the cast and bedclothes will be protected from being soiled in evacuation. The guards or wings 18 and 19 are preferably made to diverge toward their lower ends as shown for better protection of the cast and bedclothes against soiling. In ordinary use the baby is laid prone, with its upper body on a pillow 40 or other cushion placed upon the top of the support 10 above the transverse saddle 15. The child is so positioned that the portion of the cast 30 about the waist of the child seats in the recess 16 in the saddle member 15 and the leg portions of the cast seat in the sockets 20 and 21 of the wing members 18 and 19. The child is then fastened in place by the strap or straps 45 attached to the saddle member 15.

The child can be left on this combined couch and bedpan support at all times with the bedpan 28 in forward position against the wall 26. A hoop member 29 may be secured at opposite ends to the wings 18 and 19 so as to support the bedclothes in position to keep the infant warm but clear of the infant so that they will not be soiled. The child can be left on the couch all day and all night. Inasmuch as an infant is not able to give advance notice as to just how he is going to evacuate, it is preferable to leave the child face down on the couch. However, in instances where it is obvious that the child desires to defecate, the child can be picked up off the couch and laid back down upon it. The bedpan 28 can readily be slipped into or removed from the device for cleaning.

Blocks 46 may be secured under the upper end of support 10 in opposite corners thereof, which are of the same height as the walls of receptacle 25 to prevent the couch from tipping.

Obviously the support 10 and sideboards 18 and 19 can each be made in two or more parts adjustable longitudinally and transversely with reference to one another so as to take care of the growth of a child. It will be understood, also, that while the invention has been illustrated in connection with a device for a child's use, it has application also to combined couches and bedpan supports for adult patients. While the invention has been illustrated, then, in connection with a specific embodiment thereof and a specific use therefor, it is capable of further modification. This application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention what I claim is:

1. A combined convalescent couch and bedpan holder on which a patient may lie prone comprising a support having an opening therein through which the patient may evacuate, a saddle member extending transversely across said support and having a socket therein to receive a portion of the patient's torso, a pair of restraining members disposed at opposite sides, respectively, of said opening and having sockets therein to receive the legs of the patient with the legs straddling said opening, and means for supporting a bedpan beneath said opening.

2. A combined convalescent couch and bedpan holder on which a patient may lie prone comprising a support having an elongated opening therein which extends from one end thereof to a point intermediate the ends of said support, said opening being open at the said one end of said support and closed at its opposite end, a saddle member extending transversely across said support at approximately the closed end of said opening and having a socket therein to receive a portion of the patient's torso, a pair of restraining members extending respectively along opposite sides of said opening and having sockets therein to receive, respectively, the two legs of the patient with the legs straddling said opening, and a holder secured beneath said support and closed on three sides but open at the same end as said opening, said holder providing a housing into which a bedpan may be slid to register with said opening.

3. A combined convalescent couch and bedpan holder on which a patient may lie prone comprising a support having an elongated opening therein which extends from one end thereof to a point intermediate the ends of said support, said opening being open at the said one end of said support and closed at its opposite end, a saddle member extending transversely across said support at approximately the closed end of said opening and having a socket therein to receive a portion of the patient's torso, a pair of restraining members extending respectively along opposite sides of said opening and having sockets therein to receive, respectively, the two legs of the patient with the legs straddling said opening, and a holder secured beneath said support and closed on three sides but open at the same end as said opening, said holder providing a housing into which a bedpan may be slid to register with said opening.

55 RAYMOND F. HYLAND.
